United States Patent Office

Des. 211,369
Patented June 11, 1968

211,369

COMBINED MAP HOLDER AND VIEWER THEREFOR

Morley Hitchcock, Lake County, Ohio (8846 King
Memorial Road, Mentor, Ohio 44060)

Filed May 11, 1967, Ser. No. 7,081

Term of patent 14 years

(Cl. D33—3)

The figure is a perspective view of a combined map holder and viewer showing my design.

The side edge not shown is the mirror image of the side shown while the back is conventional.

I claim:

The ornamental design for a combined map holder and viewer therefor, as shown and described.
